UNITED STATES PATENT OFFICE.

SAMUEL WALLACH, OF NEW YORK, N. Y.

CLASP FOR BRACELETS.

SPECIFICATION forming part of Letters Patent No. 293,825, dated February 19, 1884.

Application filed January 11, 1884. (No model.)

To all whom it may concern:

Be it known that I, SAMUEL WALLACH, of the city and State of New York, have invented an Improvement in Clasps for Bracelets, of 5 which the following is a specification.

Bracelets have heretofore been made of ornamental flat chains, and usually the chain of each bracelet is fastened at one end to an ornamental center-piece, and the other end 10 comes around and passes through the same center-piece, and friction is applied so that the chain can be drawn along in the slide to enlarge the bracelet for allowing it to be passed over the hand, then the chain is drawn up to 15 tighten it around the wrist. There is hence a free end of the chain, which hangs down and is very inconvenient, and the party wearing the bracelet usually needs assistance in drawing up the chain around the wrist.

20 My invention is intended for fastening the chain in a very strong and reliable manner, and for allowing the same to be enlarged or contracted to fit any wrist of ordinary size.

In the drawings, Figure 1 is a plan view of 25 the fastening as open. Fig. 2 is a section of the same, and Fig. 3 is a cross-section of the clasp.

The chain *a* is to be of any desired character. I have represented it as of rings closely 30 set together, as usual in making these chains. The clasp that receives the ends of the chain is to be of any ornamental shape; but it is hollow, having a bottom, *c*, sides *b b*, and top or lid *d*, which lid is hinged at *e* to one of the 35 sides of the clasp, and can be opened or closed, there being a spring-catch to hold the same closed. Usually the balls *i i* pass against the ends of the prongs *s*, and their centers slightly below such prongs, so as to require the application of some little force to spring the lid 40 open, or to close it. The clasp is open at the ends for the reception of the chain, and one end of the chain is held firmly by a pin, *l*, pass-

ing through the links, or in any other suitable manner. The other end of the chain terminates as a cross-bar, *r*, that is longer than the width of the chain, and there are in the sides *b b* notches or recesses to receive the ends of the cross-bar. These notches should be inclined downwardly and backwardly, so that 5 the bracelet will be held after the cross-bar has been entered at its ends into the two corresponding notches, the tension on the bracelet tending to draw the cross-bar down into the bottom portions of the notches, and there 5 are to be two, three, or more pairs of these notches in the inner opposite faces of the sides *b b*, so that the bracelet can be shortened by moving the cross-bar nearer to the pin *l*. When 6 the bracelet has been placed around the wrist and the cross-bar passed into its proper notches, the cover is to be closed, and the chain is thus firmly secured, so that it is not liable to become disconnected accidentally, and a very 6 convenient and handsome article is produced, which is free from the objections heretofore arising in relation to chain-bracelets.

I claim as my invention—

1. The combination, with the flat bracelet-chain, of a clasp having a bottom, sides, and a 7 hinged cover, there being grooves in the inner surfaces of the sides, and a cross-bar at the end of the chain passing into such grooves, substantially as set forth.

2. The bracelet-chain having a cross-bar at 7 one end and an attaching-pin at the other end, in combination with a clasp that is provided with a movable cover, and inclined grooves in the opposite faces of the clasp to receive the ends of the cross-bar, substantially as set forth. 8c

Signed by me this 8th day of January, A. D. 1884.

SAMUEL WALLACH.
